UNITED STATES PATENT OFFICE.

HERBERT A. WALLACE, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RELAY.

1,285,498.

Specification of Letters Patent Patented Nov. 19, 1918.

Original application filed June 23, 1914, Serial No. 846,730. Divided and this application filed May 4, 1916. Serial No. 95,803.

To all whom it may concern:

Be it known that I, HERBERT A. WALLACE, a citizen of the United States, residing at Pittsburgh, in the county of Allegheny and State of Pennsylvania, have invented certain new and useful Improvements in Relays, of which the following is a specification.

My invention relates to relays.

The present application is a division of my co-pending application, Serial No. 846,730, filed June 23, 1914, for railway signaling.

I will describe one form of relay embodying my invention, and will then point out the novel features thereof in claim.

The accompanying drawing is a view showing one form of relay embodying my invention.

Referring first to the drawing, the relay here shown comprises a top plate 19, and a base 20, which parts are separated by a glass cylinder 81, the three parts being held together by screws 77. Mounted on the top plate 19 is a magnet 51, having pole-pieces 79 and 76 shaped substantially as shown. This magnet may be of any suitable type; as here shown it is a permanent magnet. Pivotedly mounted between the pole-pieces, is an armature 52 having a winding 78. An arm 70 is rigidly fastened to the armature, and pivotally connected to this arm is a downwardly extending link 53, which in turn is pivotally connected with a rocker arm 54 which is pivotally mounted at 55 in a lug 75. Pivotedly mounted also on this lug at points 56 and 57 are two arms 58 and 59, which arms carry counterweights 60 and 61 and contact fingers 62, 63, 64 and 65.

As here shown, the fingers 65 and 63 are adapted to engage with contacts 68 and 69 respectively, which in turn are supported by studs 82 and 7 mounted in the top plate 19. Fingers 62 and 64 which are carried by arms 58 and 59, are adapted to make contact with blocks 71 and 72 respectively, which blocks are also mounted in the top plate 19. Contact arms 58 and 59 are electrically connected with posts 83 and 84 respectively by wires 73 and 74, which posts are also mounted in top plate 19.

The downward movement of arms 59 and 58 is, as here shown, limited by stops 66 and

67 respectively, but since the contact fingers 65 and 63 rest on contacts 68 and 69 when the arms are down, these contacts may be employed as stops if desired, in which case stops 66 and 67 may be omitted.

It is understood that the arms 59 and 58 and the contacts operated thereby may be duplicated, all of the arms extending to the left of standard 75 being actuated by arm 54 in the same manner as is arm 59, and all of those extending to the right being actuated as is arm 58.

When armature 52 is deenergized, counterweights 60 and 61 hold the arms 58 and 59 in such positions that they rest on stops 67 and 66, as shown, in which position contact fingers 63 and 65 engage with contacts 69 and 68 respectively. 65 70

When winding 78 is supplied with current of such polarity as to cause armature 52 to rotate in the direction of arrow 89, arm 70, which is rigidly fixed to the armature 52 will move with the armature and cause arm 53 to move upwardly, thus causing arm 54 to rotate in such direction as to raise arm 58, thus bringing contact finger 62 into engagement with block 71 and raising finger 63 out of engagement with contact 69. 75 80

When the polarity of the current in winding 78 is reversed, armature 52 will rotate in the direction of arrow 80, thereby moving link 53 downwardly. Arm 54 then rotates about point 55, as has been previously explained, but in the opposite direction, thus raising arm 59 so that finger 64 engages block 72 and finger 65 leaves contact 68.

It will be seen that when the relay is deenergized both fingers 58 and 59 rest on their stops so that both back contacts are made; but when the relay is energized one or the other of the fingers is raised according to the polarity of the current in the armature. This operation of the contacts may be utilized for the control of railway signal circuits in the manner described in the parent application above referred to, or in any other manner as readily understood by those skilled in the art. 90 95 100

Although I have herein shown and described only one form of relay embodying my invention, it is understood that various changes and modifications may be made

therein within the scope of the appended claim, without departing from the spirit and scope of my invention.

Having thus described my invention, what I claim is:

A relay comprising an operating member biased to a middle position and capable of movement in opposite directions from said middle position, two contact fingers capable of independent movement, a front and a back contact for each finger, each finger being biased to engage its back contact, and means interposed between the operating member and said fingers for moving one of

said fingers in opposition to its bias to engage its front contact when the member moves in one direction from its middle position, and for moving the other finger in opposition to its bias to engage its front contact when the member moves in the other direction from its middle position.

In testimony whereof I affix my signature in presence of two witnesses.

HERBERT A. WALLACE.
